UNITED STATES PATENT OFFICE.

WILLIAM BARR AND SAMUEL BARR, OF PHILADELPHIA, PENNSYLVANIA.

SEAT-REGISTER.

No. 921,342.

Specification of Letters Patent.

Patented May 11, 1909.

Application filed September 7, 1907. Serial No. 391,803.

To all whom it may concern:

Be it known that we, WILLIAM BARR and SAMUEL BARR, subjects of the King of Great Britain, residing in the city and county of Philadelphia and State of Pennsylvania, have invented certain new and useful Improvements in Seat-Registers, of which the following is a specification.

This invention relates to registering devices for seats adapted to be occupied by persons.

The object of the invention is to provide a simple and efficient means whereby the number of times a seat is occupied may be registered, and to this end the invention consists in the novel construction and combinations of parts hereinafter described and particularly pointed out in the claims.

Figure 1 is a front elevation of a chair having our improved seat register applied thereto. Fig. 2 is a sectional elevation thereof as on the line *a—a* of Fig. 1. Fig. 3 is a sectional view as on the line *b—b* of Fig. 2. Fig. 4 is a sectional view of the pneumatic cushion. Fig. 5 is a detail of the means limiting the upward movement of the seat.

We have illustrated our invention herein as applied to a form of chair or seat commonly used by boot-blacks. This seat comprises a casing forming the body 1 of the chair, a foot-rest 2, and a step 3 leading to the foot rest. Rising from the body 1 of the chair are the usual arm rests 4 and back 5.

The back of the seat 6 is pivotally connected as at 7 to the casing, and the back of the top 8 of the step 3 is pivotally connected to the casing as at 9, so that said seat and top may be raised and lowered on their pivotal connection. The downward movement of the top of the step 3 is limited by a bracket 39 secured to the interior of the casing, and the downward movement of the seat 6 is limited by a bracket 40 secured to the interior of the casing. The upward movement of the top of the step 3 is limited by a pin 41 engaging the wall of an opening in a bracket 42 secured to the top of the step 3, and the upward movement of the seat 6 is limited by a pin 43 engaging the pivoted link 44 depending from a bracket on the bottom of the seat 6.

The seat 6 is held normally raised on its pivotal connection by the action of a spring 10 arranged within a socket in the casing, and acting upon the bottom of the forward portion of the seat 6. Projecting down-

wardly from the forward portion of the seat 6 is an arm 11, the lower forked end of which embraces one end of a lever 12 which is fulcrumed on a bracket 13 rising from a horizontal partition 14 within the casing. The other end of the lever 12 extends to a position adjacent a movable member 15 of a registering device 16 which may be of any common and well known construction, which operates to register each time its movable member is moved. The movable member may be connected to an indicating hand or number of indicating hands geared together and operatively connected to its movable member. These registering devices are common and well known, and no detailed description thereof is deemed necessary herein. The lever 12 is held in engagement with the arm 11 by a spring 17 secured to the lever 12 and the bracket 13. Thus it will be seen that each time the seat 6 is depressed by a person occupying the chair, and is raised by the action of the spring 10 upon the removal of the person, the lever 12 will act upon the member 15 of the registering device 16 to register the occupation of the seat.

It sometimes happens that the occupant of the seat is restless, and does not keep enough pressure upon the seat 6 to maintain it depressed at all times. In order to prevent more than one operation upon the registering device for each time the seat is occupied, due to the restlessness of the person, we provide the following:—Rising from the projection 14 is a bracket 18 to which is pivoted a bell crank lever 19, one end of which is provided with a hook 20, and the other end of which is connected to the upper end of a rod 21 which extends down through the casing, and has its lower end connected to one arm of a bell crank lever 22 which is pivotally mounted on a bracket 23 rising from the bottom of the casing. The other arm of the bell crank lever 22 is pivotally connected to a rod 24 which extends to and is connected to one arm of a bell crank lever 25 pivoted to a bracket on the inside of the front wall of the step 3. The other arm of the lever 25 is provided with a roller 26 which engages a plate on the bottom of the top of the step 3 to maintain said step slightly normally elevated by the action of a spring 27 secured to the rod 24 and the rear wall of the casing. Projecting downwardly from the seat 6 adjacent the hook 20 is a bracket 26^a carrying a roller 29 which is so located with relation to the hook

20 that when the seat 6 is depressed the hook 20 may pass over and into engagement with said roller to maintain the seat in the depressed position. The moment the weight of 5 a person depresses the seat 6, the hook 20 moves into engagement with the roller 29 by the action of a spring 30 secured to the bell crank lever 19 and the seat 6. Thus it will be seen that the seat 6 will be maintained in 10 the depressed position irrespective of the restlessness of the occupant. When, however, the occupant leaves the seat and in descending his weight comes upon the top 8 of the step 3, the roller 29 will be depressed, 15 thereby moving the bell crank lever 25, the rod 24, the bell crank lever 22, the rod 21, and the bell crank lever 19 in a manner to disengage the hook 20 from the roller 29 and permit the spring 10 to raise the seat 6 ready 20 for the reception of the next occupant.

In order to prevent a rapid upward movement of the seat 6 upon its release from the hook 20, we provide a pneumatic cushion comprising a cylinder 31 having a piston 32 therein, the cylinder 31 being secured to a bracket 33 rising from the partition 14. The piston 32 is provided with a depending rod 34, the lower end of which is connected to a yoke frame 35 which extends downwardly 25 from the seat 6. Thus it will be seen that 30 the piston 32 will be raised and lowered with said seat.

Screwed into the cylinder 31 above the piston 32 is a block 36 having an opening 37 therein leading from the interior of the cylinder to the exterior thereof. Screwed into the block 36 and entering the opening 37 is a thumb screw 38 which may be adjusted to vary the size of the opening 37. During the 40 raising of the seat 6 and therewith the piston 32, the compression of the air within the top of the cylinder 31 prevents the rapid upward movement of the seat 6, and during the upward movement of the seat the compressed 45 air escapes from the cylinder 31 through the opening 37. Thus it will be seen that the

upward movement of the seat 6 may be nicely regulated by adjusting the screw 38 to vary the cross sectional area of the opening 37 leading from the cylinder.

The front wall of the casing is provided with a hinged door 45 directly in front of the registering device 16 whereby access may be had to the interior of the casing for the purpose of reading the registering device and for other purposes, including the disengagement of the link 44 from the pin 43 to permit the raising of the seat 6 beyond its usual limit for purposes of repair, &c.

We claim:—

1. In a seat register, the combination of a depressible seat, means for raising said seat, a registering device including a movable operating member, connections between said seat and said member, a pivoted hook, means on said seat for engagement by said hook to hold the seat in the depressed position, and means for operating said hook.

2. In a seat register, the combination of a depressible seat, means for raising said seat, a registering device including a movable operating member, connections between said seat and said member, a lock to hold said seat in the depressed position, a step leading to the seat, and means operated by said step for releasing said lock.

3. In a seat register, the combination of a depressible seat, means for raising said seat, a registering device including a movable operating member, connections between said seat and said member, a lock to hold said seat in the depressed position, a step leading to the seat, means operated by said step for releasing said lock, and means for cushioning the upward movement of the seat.

In testimony whereof we have hereunto affixed our signatures.

WILLIAM BARR.
SAMUEL BARR.

In the presence of—

WILLIAM J. THOMAS,
WILLIAM MACE.
